US00D797529S

(12) **United States Design Patent** (10) Patent No.: **US D797,529 S**
(45) Date of Patent: **** Sep. 19, 2017**

(54) **APPLICATOR**

- (71) Applicant: **OMS Investments, Inc.**, Los Angeles, CA (US)
- (72) Inventors: **Randy M. Goodwin**, Grove City, OH (US); **Paul Havlovitz**, Dublin, OH (US); **Ryan R. Berger**, Columbus, OH (US); **Paul Hsu**, Lewis Center, OH (US); **Michael T. Kopczewski**, Grove City, OH (US); **Timothy Michael Martin**, Westerville, OH (US); **Jay F. Perkins**, Pickerington, OH (US)
- (73) Assignee: **OMS Investments, Inc.**, Los Angeles, CA (US)
- (**) Term: **15 Years**
- (21) Appl. No.: **29/591,145**
- (22) Filed: **Jan. 17, 2017**

Related U.S. Application Data

- (63) Continuation of application No. 29/532,941, filed on Jul. 13, 2015, now Pat. No. Des. 779,898, which is a continuation of application No. 29/475,913, filed on Dec. 9, 2013, now Pat. No. Des. 736,577, which is a continuation of application No. 29/433,244, filed on Sep. 27, 2012, now abandoned, which is a continuation of application No. 29/386,483, filed on Mar. 1, 2011, now Pat. No. Des. 670,982.

(57) **CLAIM**

The ornamental design for an applicator, as shown and described.

DESCRIPTION

FIG. 1 is a perspective view of an applicator.

FIG. 2 is a front elevation view thereof.

FIG. 3 is a rear elevation view thereof.

FIG. 4 is a side elevation view thereof.

FIG. 5 is an opposite side elevation view thereof.

FIG. 6 is a top plan view thereof; and,

FIG. 7 is a bottom plan view thereof.

The broken line showings of the applicator are included for the purpose of illustrating portions of the article and form no part of the claimed design.

1 Claim, 6 Drawing Sheets
